UNITED STATES PATENT OFFICE.

HENRY DAVIS, OF BALTIMORE, MARYLAND.

BRAKE FOR RAILROAD-CARS.

Specification of Letters Patent No. 25,392, dated September 13, 1859.

To all whom it may concern:

Be it known that I, HENRY DAVIS, of the city and county of Baltimore and State of Maryland, have invented an Improved 5 Apparatus for Arresting the Forward Movement of Railway-Cars; and I do hereby declare that the following is a full and exact description thereof, reference being had to the accompanying drawings, which constitute a part of this specification.

Figure 1, is a top view of a car-truck which has my improved car-arresting apparatus combined therewith; Fig. 2, is a side view of the same, and Fig. 3, is a section in 15 the line x, x , of Fig. 1.

Similar letters indicate like parts in each of the drawings.

My improvement in the means which are ordinarily employed for arresting the forward movement of railway-cars, consists in the combination of sand receptacles with the trucks and with the brakes of a railway-car in such a manner that small quantities of sand can be let in between the faces of the 20 brakes and the peripheries of the wheels, at the instant that the former are made to press against the latter, for the purpose of thereby increasing the frictional action of the brakes upon the wheels.

30 In the drawings the sand-boxes C, C, are represented as secured between the side beams A, B, of a car-truck, and in such positions respectively that the necks which descend from said boxes will conduct the sand 35 into flaring openings at the upper ends of the frictional surfaces of the car-brakes.

The body D, of a pair of car-brakes is suspended between a pair of car-wheels by means of a rack-bar f, which works in a vertical aperture in either end of the central bearing beam E. The pinion k, whose teeth work into the teeth of the rack-bar f, is placed upon a short shaft e, whose journal-boxes are combined with the blocks G, which 45 are bolted to the under surface of either end of the said bearing beam E. The blocks G, also receive the journal-boxes of a roller h, which bears against the back of the rack-bar f. A hinged cover j, closes a discharging 50 aperture in the neck of each sand-box, which covers are connected to the upper end of the rack-bar f, by means of a pair of angular levers i, i, as shown in Fig. 3; viz: The inner

ends of the said angular levers are jointed to the upper end of the rack-bar. At their 55 angles the said levers are combined with pivot-pins which project from the outer angles of the transverse beams F, F, and the lower ends of these levers pass into pockets or loops formed upon the backs of 60 the said hinged covers. (j j) It will therefore be perceived that the opening of the covers of the discharging apertures in the necks of the sand boxes (C, C,) must be simultaneous with the action of the brakes 65 upon the car-wheels, and that the sand must pass from the sand-boxes directly in between the peripheries of each car-wheel and the flaring upper end of the frictional surface of its brake; and also that the said apertures in 70 the necks of the sand boxes will be closed by the act of withdrawing the brakes from the peripheries of the car-wheels. That greatly additional frictional power will be given to the brakes by the introduction of a 75 small quantity of sand between their friction surfaces and the peripheries of the car-wheels, at the time that the former is brought to bear upon the latter, is self-evident.

The drawings represent a crank b, as secured to the outer end of each pinion-shaft e, and straight bars g, g, as being combined with the wrists of the said cranks. Chains are represented as being connected to each end of the bars g, g, which may be connected 85 to any suitable apparatus for operating the brakes, or for connecting the brakes of one truck or car with those of the adjoining truck or car.

What I claim as my invention and desire 90 to secure by Letters Patent, is—

Increasing the frictional action of car-brakes upon the peripheries of car-wheels by the introduction of sand, or its equivalent, 95 between the frictional surfaces at the time that the brakes are brought in contact with the car-wheels, substantially as herein set forth.

The above specification of my improvement in the brakes of railway-cars signed 100 and witnessed this 15th day of July 1859.

HENRY DAVIS.
